ELECTRICAL UNIT FOR HEATING AND TOASTING SANDWICHES

Peter A. Krane, Clayton, Mo.

Application January 30, 1956, Serial No. 39,957

Term of patent 7 years

(Cl. D81—10)

FIG. 1.

FIG. 2.

FIG. 3.

FIG. 4.

Fig. 1 is a top plan view of my new design for an electrical unit for heating and toasting sandwiches;

Fig. 2 is a front elevational view;

Fig. 3 is a rear elevational view; and

Fig. 4 is an end elevational view.

I claim:

The ornamental design for an electrical unit for heating and toasting sandwiches, as shown.
